UNITED STATES PATENT OFFICE.

FRANK COSS, OF GREENCASTLE, INDIANA.

FLOUR-SIFTER.

1,260,515.

Specification of Letters Patent. Patented Mar. 26, 1918.

Application filed May 14, 1917. Serial No. 168,405.

To all whom it may concern:

Be it known that I, FRANK Coss, a citizen of the United States, residing at Green-
castle, in the county of Putnam and State of
Indiana, have invented a new and useful
5 Flour-Sifter, of which the following is a
specification.

It is the object of my invention to provide
a flour sifter which at once is sanitary and
10 easy to clean, prevents packing, sifts with
greater rapidity than the usual sifter, and is
simple and easy to manufacture.

The accompanying drawing illustrates my
invention. Figure 1 is a vertical central
15 section through the sifter and the lower part
of the associated flour bin, embodying my
invention; Fig. 2 is a plan of the sifter oper-
ating mechanism and casing, with the rotat-
20 able dome-shaped sifter screen removed;
and Fig. 3 is a bottom view of such rotat-
able dome-shaped sifter screen.

The flour bin usually has a funnel-shaped
lower portion 10, terminating in a neck 11,
and removably mounted upon this neck by
25 any suitable fastening 12 is the upper cylind-
rical portion of the sifter casing 13, below
which is a funnel-shaped portion 14, the
parts 13 and 14 at their junction being pro-
30 vided with an internal annular shoulder 15.
Upon this shoulder rests the edge of a dome-
shaped sifter screen 16, usually a wire screen
for rigidity, which screen is provided at the
35 edge which rests upon the shoulder 15 with
a circular strengthening wire 17 the two op-
posite points of which are connected by a
diametrical bridge 18, which is of sheet
metal and at its middle portion is of an in-
40 verted U-shape in cross section. The top of
this inverted U-shaped bridge is provided
at the center with a hole 19, which is in the
axis of the dome 16, and this hole receives
45 the upper end of a shaft 20 mounted in a
suitable frame work 21 supported within
the funnel 14. Near its upper end the shaft
20 is bent to form a crank arm 22, which is
50 received into the inverted U-shaped bridge
18 so as to form a driving connection be-
tween the shaft and the bridge. The shaft
20 is provided with a suitable gear 23 which
55 meshes with a gear 24 on an operating crank
25, the gears 23 and 24 preferably being
mounted within the frame work 21, which
is preferably bent into such shape as to form
a covering for such gears to protect them
60 from the sifted flour.

By operating the crank 25, the dome 18 is
turned about its vertical axis by reason of
the driving connection between the crank 22
and bridge 18. This effectively sifts the
flour which is fed downward from the bin 60
above. I have found that this sifting takes
place very rapidly with substantially no
clogging when the screen is dome-shaped
as shown, sifting much more rapidly and
with much less clogging than if the screen 65
has any other shape, such as being flat or
concave upward. In addition, this sifting
is practically without wear on the screen, as
the only friction of the screen is with the
flour itself. The screen is balanced by the 70
coöperation of the wire 17 at its edge and
the shoulder 15, upon which such wire slides.
If desired, in order further to prevent clog-
ging, a curved bridge wire 26 supported in
the neck 11 may be arranged above the rotat- 75
ing screen 16, so that it just clears the
screen as the latter rotates. This makes
a substantially self-cleaning construction.
However, for additional cleaning such as is
80 always desirable, it is only necessary to re-
lease the fastenings 12 and remove the sifter
and its casing 13 from the neck 11, where-
upon the dome-shaped sifter screen may be
readily lifted out, the driving connection 85
between the shaft 20 and the bridge 18 per-
mitting such separation. If necessary for
any reason, as by some breakage of the
screen, a new screen may be substituted by
merely putting it in place on the upper end 90
of the shaft 20. When this is done the 90
screen positions itself.

I claim as my invention:

1. A flour sifter, comprising a casing hav-
ing an annular shoulder, a dome-shaped
screen removably mounted within said cas- 95
ing so that its edge coöperates with said
shoulder, a vertical shaft mounted in said
casing below said screen and having a driv-
ing connection therewith for producing ro-
tation of the screen when the shaft is ro- 100
tated, and means for rotating said shaft.

2. A flour sifter, comprising a casing hav-
ing an annular shoulder, a dome-shaped
screen removably mounted within said cas- 105
ing so that its edge coöperates with said
shoulder, a vertical shaft mounted in said
casing below said screen and having a driv-
ing connection therewith for producing ro-
tation of the screen when the shaft is ro- 110
tated, and means for rotating said shaft,

said driving connection being releasable by merely lifting the screen from said shoulder and the upper end of said shaft.

3. A flour sifter, comprising a casing, an upwardly convex dome-shaped screen removably mounted for rotation within said casing, a vertical shaft below said screen and having a driving connection therewith, and means for rotating said shaft to produce 10 rotation of said screen.

4. A flour sifter, comprising a casing, an upwardly convex dome-shaped screen removably mounted for rotation within said casing, a vertical shaft below said screen and having a driving connection therewith, and means for rotating said shaft to produce rotation of said screen, said driving connection being formed by a diametrical bridge member connecting opposite points 15 on the edge of said screen below the screen

proper, said bridge member having a central opening for receiving the upper end of the vertical shaft and a middle portion of inverted U-shaped cross section, and said shaft being provided with a lateral projection located in said U-shaped portion. 25

5. A flour sifter, comprising a casing, an upwardly convex dome-shaped screen removably mounted for rotation within said casing, a vertical shaft below said screen and 30 having a driving connection therewith, a horizontal operating shaft provided with an operating crank, and gearing connecting said horizontal and vertical shafts.

In witness whereof, I have hereunto set 35 my hand at Indianapolis, Indiana, this 9th day of May, A. D. one thousand nine hundred and seventeen.

FRANK COSS.
